Primary Examiner — Zenia Bennett*(74) Attorney, Agent, or Firm* — Fitch, Even, Tabin & Flannery LLP(57) **CLAIM**

We claim the ornamental design for a swim board, as shown and described.

DESCRIPTION

FIG. 1 is a front perspective view of a swim board; FIG. 2 a rear perspective view of the swim board of FIG. 1; FIG. 3 is a front elevational view of the swim board of FIG. 1; FIG. 4 is a right side elevational view of the swim board of FIG. 1; FIG. 5 is a bottom plan view of the swim board of FIG. 1; FIG. 6 is a top plan view of the swim board of FIG. 1; FIG. 7 is a left side elevational view of the swim board of FIG. 1; and, FIG. 8 is a rear elevational view of the swim board of FIG. 1. The broken lines shown are included for the purpose of illustrating the unclaimed portions of the swim board and form no part of the claim.
